Primary Examiner — Mark T. Philippss

(57) **CLAIM**

The ornamental design for a linear actuator machine as shown and described.

DESCRIPTION

1. Linear actuator machine
2. Linear actuator machine
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom
